DESIGN FOR A BOX OR SIMILAR ARTICLE

Willard B. Golovin, New York, N. Y., assignor to Willard B. Golovin, Inc., New York, N. Y.

Application October 16, 1940, Serial No. 95,860

Term of patent 7 years

To all whom it may concern:

Be it known that I, Willard B. Golovin, a citizen of the United States, residing in New York, New York, have invented a new, original, and ornamental Design for a Box or Similar Article, of which the following is a specification, reference being had to the accompanying drawing, forming a part thereof.

Fig. 2 is a side view thereof, both sides having substantially the same appearance.

Fig. 3 is a perspective view thereof.

I claim:

The ornamental design for a box or similar article, substantially as shown.

WILLARD B. GOLOVIN.
